GASEOUS DISCHARGE TUBE

Alfons Kauffeldt, Berlin, Germany, assignor to
Telefunken Gesellschaft für Drahtlose Tele-
graphie m. b. H., Berlin, Germany, a corpora-
tion of Germany

Application June 12, 1937, Serial No. 147,852
In Germany July 4, 1936

4 Claims. (Cl. 250—27.5)

My invention relates to electron discharge de-
vices, more particularly to improvements in such
devices of the gaseous discharge type.

The invention is concerned with tubes pos-
sessing a so-called drooping characteristic, for
instance, tubes operating with a gas atmosphere
or filling. The difficulty residing in the control
of gaseous tubes is due to the fact that electrodes
operated with a negative biasing potential are
10 at once surrounded with a neutralizing positive
space charge so that, even at extremely small
distances from the electrode, control action is
entirely precluded.

This difficulty has in the past been circumvent-
15 ed by disposing the electrodes at such close prox-
imity to one another that their mutual distance
was less than the mean free path of the elec-
trons, thereby precluding all changes of any ap-
preciable ionization taking place in the inter-
20 vening space. While it is true that this affords
a means to control large currents, the efficiency
of tubes of this kind is not particularly high.

The object of my invention is to provide an
electron discharge device of the gaseous type
25 having improved characteristics and a circuit
therefor.

The novel features which I believe to be char-
acteristic of my invention are set forth with par-
ticularity in the appended claims, but the inven-
30 tion itself will best be understood by reference
to the following description taken in connection
with the accompanying drawing in which Figure
1 is a diagram illustrating the fundamentals of
my invention, Figure 2 is a schematic diagram
35 of a circuit employing my invention, and Figure
3 is a schematic diagram of an electron discharge
device in section embodying my invention and a
circuit therefor.

Now, the present invention is predicated upon
40 the idea that every gas discharge is controllable
by its plate potential. Of course, directly ap-
plied, such a control would serve no practical
purpose at all for it would lack amplification.
But the control action following is feasible, that
45 is connecting in parallel relation to a gas or glow
tube, a device the resistance or current con-
ductivity of which may be controlled in some
suitable way without consumption of power. In
50 the presence of a definite resistance of the par-
allel connected device a "summational" char-
acteristic for both devices is obtained by adding,
for the same potential, the corresponding cur-
rents. Hence, for different resistances there re-
55 sults a family of curves or characteristics, and

this family of curves comprises a controllable
range.

The principle of my invention follows from a
study of Figures 1 and 2 of the attached drawing.
Referring to Figure 1, G denotes the schematic
characteristic of a glow discharge, while P is a
family of characteristics of the parallel con-
nected device. As regards the latter, devices
possessing such characteristics are known in the
prior art, and the various graphs are obtainable
10 in the absence of energy dissipation, G+P is
the family of summational curves resulting from
a parallel connection of the two devices.

It is known in the art that a glow discharge
is stabilizable by the aid of a series resistance, the
latter having, however, to be so proportioned that
its characteristic will intersect the glow discharge
characteristic at only one point if plotted as a
function of E—U, where E is a constant D. C.
voltage of suitable value, and U the potential pre-
vailing across the resistance. It can be readily
seen from Figure 1, that according to the choice
of the parallel resistance P, the discharge is
20 stabilized at another potential, namely at a
voltage for which the load line W will intersect
25 the corresponding summational characteristic
G+P. Upon the whole there results an oper-
able range marked by J₁ U₁ and J₂ U₂.

No special assumption has been made in re-
gard to the parallel device P. But the same
30 may consist either of a high vacuum tube or else
it may consist of a controllable gas discharge.
The output resistance W (Figure 2), for instance,
could consist of the primary winding of an out-
put transformer.

Now, according to this invention the two de-
vices P and G are united into one discharge sys-
tem in such a way that in a gas or vapor filled
vessel (B) a non-apertured anode A and an
apertured cathode K are fitted into a frame J
35 made of a suitable insulation material in such
a way that between them a confined or closed
space results, and that the mutual distance be-
tween them is less than the mean free path of
the electrons. Between anode and cathode, 40
finally, is a control electrode S which is also aper-
tured and which, inside the space, mutually cov-
ers the two first named electrodes. The cathode
is preferably coated.

If by way of a useful resistance W a suitable
50 potential E be applied to the two outer electrodes,
a glow discharge about the insulation frame may
be struck and maintained between the outer sur-
faces of the cathode and the anode since these
surfaces are separated a distance greater than 55

the mean free path of an electron in the gas within the envelope. Evidently, in this instance, however, an electronic discharge also occurs from the cathode to the anode across the inner space. 5
At the cathode, as a result of impacts of the positive ions from the negative glow discharge, electrons are produced, and inasmuch as the field intensity prevailing in the inner space exceeds that in the outer space (as a result of prevailing distances), part of the electrons originating 10 at the cathode will be directly withdrawn to the plate. Referred to the main discharge about the insulation part J, this electronic discharge, therefore, represents a shunt just as in Figure 2. The 15 current flow (transmissibility) of this shunt is regulable by control grid S so that exactly the case of Figure 2 results. Under certain circumstances it may be preferable to dispose anteriorly of the control grid a screen grid which is operated on a suitable positive bias in order to preclude from the control grid such positive ions as happen to fly through the cathode apertures.

It will be seen from Figure 1 that the efficiency will be greater the smaller the current flowing 25 through the parallel resistance P. If the resistance line characteristic W is made steeper, the range of current which can be controlled becomes greater.

In lieu of a cold cathode K shown in Figure 3, 30 it would, of course be feasible also to use a thermionic type of cathode. The incandescing thereof may be direct or indirect, and the same may be coated with emissive oxide. Moreover, this cathode could be either apertured, say, in the form 35 of a grid, or it could be impermeable, i. e., non-apertured (or solid). Further, only one side or face of the cathode could be coated with oxide, and the heat dissipated on the cathode as a result of the main discharge could be used for heating.

40 Inasmuch as the summational characteristic of the arrangement is of a drooping nature, circuit arrangements can be assembled which are predicated for their operation upon a device with a drooping characteristic, above all, for de-attenuation (regeneration) of an oscillation circuit or 45 the production of oscillations.

The material from which frame J may be made consists preferably of low-loss refractory ceramic substances. The frame proper is so constructed 50 as to insure a biasing tension, in other words, the frame imparts to the electrodes at least in one direction of their surfaces a mechanical tension with a view to keeping them taut.

While I have indicated the preferred embodiments of my invention of which I am now aware and have also indicated only one specific application for which my invention may be employed, it will be apparent that my invention is by no means limited to the exact forms illustrated or 55 the use indicated, but that many variations may be made in the particular structure used and the purpose for which it is employed without departing from the scope of my invention as set forth in the appended claims.

60 65 I claim:

1. An electron discharge device including an envelope having a gaseous atmosphere, electrodes within said envelope having surfaces spaced from each other less than the mean free path of an 70 electron in said gaseous atmosphere, and a control element positioned between said surfaces, in-

sulating means for supporting said electrodes and control element in spaced relationship, said surfaces and said insulating supporting means enclosing a space in which a gaseous discharge cannot take place, said electrodes having surfaces 5 outside of said enclosed space exposed to the gaseous atmosphere within the envelope and spaced apart a distance greater than the mean free path of an electron in the gas for providing an ionizable path between the electrodes on the 10 outside of said space whereby a gaseous discharge may take place between the outside surfaces of said electrodes.

2. An electron discharge device including an envelope having a gaseous atmosphere, electrodes 15 of sheet material each having a surface spaced from the surface of the other electrode less than the mean free path of an electron in the gaseous atmosphere and a control member positioned between said surfaces, insulating means for supporting 20 said electrodes and control member in spaced relationship, said surfaces and said insulating means enclosing a space in which a gaseous discharge cannot take place under operating conditions, the other surfaces of said electrodes being exposed 25 to the gaseous atmosphere within the envelope, said other surfaces being spaced apart a distance greater than the mean free path of an electron in the gaseous atmosphere whereby a gaseous discharge can take place between the other surfaces 30 of said electrodes.

3. An electron discharge device including an envelope having a gaseous atmosphere, a plurality of flat electrodes having surfaces spaced from each other less than the mean free path of an 35 electron in said gaseous atmosphere, a control grid positioned between said surfaces, insulating means for supporting said electrodes and said control grid in spaced relationship and providing with said surfaces an enclosed space in which a gaseous 40 discharge cannot take place during normal operation of the device, the surfaces of said electrodes outside the enclosed space being exposed to the gaseous atmosphere within the envelope and spaced a distance greater than the mean 45 free path of an electron in the gaseous atmosphere whereby a gaseous discharge may take place between the surfaces of said electrodes outside the enclosed space.

4. An electron discharge device including an 50 envelope having a gaseous atmosphere, a plurality of flat electrodes having surfaces spaced from each other less than the mean free path of an electron in said gaseous atmosphere, a control grid positioned between said surfaces, insulating 55 means for supporting said electrodes and said control grid in spaced relationship and providing with said surfaces an enclosed space in which a gaseous discharge cannot take place during normal operation of the device, the surfaces of said 60 electrodes outside said enclosed space being exposed to the gaseous atmosphere within the envelope and spaced a distance greater than the mean free path of an electron in the gaseous atmosphere whereby a gaseous discharge may take place 65 between the surfaces of said electrodes outside the enclosed space, one of said flat electrodes being an anode and the other of said electrodes being a perforated cathode.
